FIG. 1

FIG. 2

FIG. 1 is a perspective of a tire showing our new design, it being understood that the design is repeated throughout the circumference of the tire as shown schematically by the solid lines, the opposite side being substantially the same as that shown; and

FIG. 2 is a cross-sectional view thereof taken on line 2—2 of FIG. 1.

We claim:

The ornamental design for a tire, substantially as shown and described.
